(57) **CLAIM**

We claim the ornamental design for vehicular dashboard controls, as shown and described.

DESCRIPTION

FIG. 1 is a top and rear perspective view showing vehicular dashboard controls of our new design;

FIG. 2 is a top plan view showing the vehicular dashboard controls of our new design;

FIG. 3 is a side plan view showing the vehicular dashboard controls of our new design; and,

FIG. 4 is a side plan view, taken opposite that of FIG. 3, showing the vehicular dashboard controls of our new design. The broken lines (for example, a dashboard) are for illustrative purposes only and form no part of the claimed design.
